UNITED STATES PATENT OFFICE

2,004,459

DINGER

Charles Boehnke, Rosemead, Calif.

Application December 3, 1934, Serial No. 755,801

3 Claims. (Cl. 81—15)

The present invention relates to a dinger or spotting tool used in raising small depressions on a damaged metal surface.

The object of the invention resides in the provision of a tool of this nature which will facilitate the spotting and removing of small dents.

Another very important object of the invention resides in the provision of a tool of this nature which is simple and rugged in construction, thoroughly reliable in use, easy to manipulate, convenient, and otherwise well adapted for the purpose to which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a longitudinal section through a tool embodying the features of my invention.

Figure 2 is a side elevation thereof.

Figure 3 is a sectional view taken substantially on the line 3—3 of Figure 1.

Figure 4 is a fragmentary bottom plan view of one end of the tool.

Referring to the drawings in detail it will be seen that the numeral 5 denotes an elongated base one end of which merges into an elongated curved shank 6 which extends over the base and terminates in a flexible elongated indicator 7, the end of which is above the other end of the base. Under the base 5 there may be bolted or otherwise secured a file 8. On the base adjacent 30 said other end there is formed a longitudinally extending cylinder 9, the upper portion of one end of which is provided with a longitudinally extending slot 10. The other end of the cylinder is internally threaded to receive a plug 11. A piston 12 is slidably in the cylinder. A coil spring 14 is disposed in the cylinder and impinges against the piston and the plug 11 and tends to force the piston out of the cylinder. A pair of extensions 15 are mounted on said one end of the cylinder being formed integrally therewith and also with the base and terminate in a short collar 16 which is vertically disposed and internally threaded. A cylinder 17 has its lower end threaded in this collar. A striking pin 18 is slidably mounted in the cylinder. A triangular member 19 is pivotally mounted as at 20 between the extensions. This member 19 is disposed between the striking pin 18 and the piston or plunger 12. Lugs 20 rise from the other end of the base and a trigger 21 is rockable therebe-

tween as at 22. An elongated rod 23 is pivotally engaged with the trigger as at 24 and has a hook end 25 on which is formed an inclined edge 26. A rockable guide hood 27 extends across the extension 15 and over the slot 10. A spring 28 is attached to the rod 23 and to the cylinder 9 and normally holds the parts in the position shown in Figure 1. A spring 29 extends over the hood guide 27 and has its ends attached to the cylinder. This hood guide is pivotally mounted on the pin 20.

The operation of this device is as follows: The flexible indicator 7 is placed on the upper or visible side of the metal with the point on the depression and it will be noted that this point is immediately above the point of the striking pin which cannot be seen at this time. In this manner the point of the striking pin is directly beneath the point of the indicator. Then by pulling the trigger to the right, as shown in my drawings, the rod conveys this movement to the hook end thereof. The hook catches the end of the piston or plunger and forces it against the tension of the spring 14. When the hook reaches the end of the slot 10 the inclined edge thereof 26 causes the hook to slip off the piston. When this takes place, the piston flies against the triangular pivoted member 19 which transmits its movement to the striking pin forcing the same upward. Upon the completion of these actions, the trigger returns to its original position by means of the spring 28. The purpose of the spring 29 is to keep the hook end 25 in normal engaging position. The plug 11 is adjustable to control the force of the blow. The metal file 8 may be used if desired to complete the smoothing out of the metal.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A tool of the class described including a base, a cylinder mounted longitudinally on the base, a piston in the cylinder, a spring normally urging the piston out of the cylinder at one end, said one end being provided with a longitudinally extending slot, a rockable member opposite the slotted end of the cylinder, means for mounting the rockable member, a second cylinder, said second cylinder being mounted at right angles to the first mentioned cylinder and opposite the rockable member, a trigger, means for rockably mounting the trigger on the other end of the base, a rod pivotally engaged with the trigger and extending along the outside of the first cylinder and having a hook end extending into the slot for engaging the end of the piston, means for urging said hook end toward the piston and a striking pin slidable in the second cylinder and engageable by the rockable member. 5
- 10 2. A tool of the class described including a base, a cylinder mounted longitudinally on the base, a piston in the cylinder, a spring normally urging the piston out of the cylinder at one end, said one end being provided with a longitudinally extending slot, a rockable member opposite the slotted end of the cylinder, means for mounting the rockable member, a second cylinder, said second cylinder being mounted at right angles to the first mentioned cylinder and opposite the rockable member, a striking pin slidable in the second cylinder and engageable by the rockable member. 10
- 15 3. A tool of the class described including a base, a cylinder mounted longitudinally on the base, a piston in the cylinder, a spring normally urging the piston out of the cylinder at one end, said one end being provided with a longitudinally extending slot, a rockable member opposite the slotted end of the cylinder, means for mounting the rockable member, a second cylinder, said second cylinder being mounted at right angles to the first mentioned cylinder and opposite the rockable member, a striking pin slidable in the second cylinder and engageable by the rockable member. 15
- 20 2. A tool of the class described including a base, a cylinder mounted longitudinally on the base, a piston in the cylinder, a spring normally urging the piston out of the cylinder at one end, said one end being provided with a longitudinally extending slot, a rockable member opposite the slotted end of the cylinder, means for mounting the rockable member, a second cylinder, said second cylinder being mounted at right angles to the first mentioned cylinder and opposite the rockable member, a striking pin slidable in the second cylinder and engageable by the rockable member, a trigger, means for rockably mounting the trigger on the other end of the base, a rod pivotally engaged with the trigger and extending along the outside of the first cylinder and having a hook end extending into the slot for engaging the end of the piston, a rockable guide 25 engaging the rod and spring means associated therewith for normally holding said hook end in engaging position with respect to the piston, a shank extending from said other end of the base and being curved over the base and merging into a flexible elongated indicator terminating opposite the end of the striking pin. 20
- 25 30

CHARLES BOEHNKE.
